UNITED STATES PATENT OFFICE.

CHARLES F. BOLDT, OF DETROIT, MICHIGAN.

HONING-MACHINE.

No. 820,761.

Specification of Letters Patent.

Patented May 15, 1906.

Application filed July 27, 1905. Serial No. 271,477.

To all whom it may concern:

Be it known that I, CHARLES F. BOLDT, a citizen of the United States, residing at Detroit, in the county of Wayne, State of Michigan, have invented certain new and useful Improvements in Honing-Machines; and I do declare the following to be a full, clear, and exact description of the invention, such as will enable others skilled in the art to 10 which it appertains to make and use the same, reference being had to the accompanying drawings, and to the figures of reference marked thereon, which form a part of this specification.

15 This invention relates to a machine for honing razors; and it consists in the construction and arrangement of parts hereinafter fully set forth, and pointed out particularly in the claims.

20 The object of the invention is to provide simple and efficient means for honing the blade of a razor by the rotation of cylindrical stones and to provide for steadyng the razor when being operated upon and directing it properly between the stones.

25 The above object is attained by the mechanism illustrated in the accompanying drawings, in which—

Figure 1 is a side elevation of a machine 30 embodying my invention, showing a razor-blade in position for honing. Fig. 2 is an end elevation of Fig. 1, the tang of the blade being in section. Fig. 3 is a plan view of the machine. Fig. 4 is an enlarged transverse 35 section as on line 4 4 of Fig. 1. Fig. 5 is a perspective view of the slotted guide-plate in which the blade is held while being honed.

Referring to the characters of reference, 1 indicates a suitable frame in which are journaled the shafts 2 and 3, respectively, upon 40 which the cylindrical honing-stones 4 and 5 are mounted. The shaft 2, as shown by dotted line 6 in Fig. 4, passes through horizontally-slotted openings in the frame, thereby 45 permitting said shaft and the cylindrical stone 5 to be moved toward and from the stone 4. Connecting the ends of the shafts 2 and 3 at each end is a coiled spring 7. The tension of said springs is exerted to draw the 50 stones together, whereby their peripheries are always maintained in contiguous working relation.

Upon the projecting ends of the shafts 2 and 3 are the grooved wheels 8 and 9, respectively, and mounted upon a short jour-

nal-bolt 10, which is adapted to adjust vertically in a slot 11, (shown by dotted lines in Fig. 2,) is a grooved idle wheel 12. Journaled at 13 at the end of the frame is a grooved driving-wheel 14, having a projecting handle 15, through the medium of which said wheel may be rotated. Passing around the driving-wheel, over the idle wheel 12, and under and over the grooved wheels 8 and 9, respectively, is a driving-belt 16, whereby 60 through the rotation of the driving-wheel the shafts 2 and 3 and the cylindrical grinding-stones 4 and 5 thereon are caused to revolve in unison in opposite directions. By an adjustment of the idle wheel 12 a proper tension upon the belt may be made.

It is necessary that the blade 17 of the razor be presented squarely between the grinding-stones and held perfectly in position during the operation of honing to obviate 75 grinding more upon one side than the other. This result is accomplished by means of the supporting-plate 18, having a longitudinal slot 19 therein, through which the blade of the razor is adapted to extend. At the ends 80 of said plate are the hangers 20, having the angular end portions 21, provided with squared apertures 22, adapted to receive the posts 23, projecting vertically from the ends of the frame. Surrounding said posts and 85 confined between the angular end portions of the hangers and the top of the frame are the coiled compression-springs 24, whereby the plate 18 is normally held suspended, but permitting said plate to be depressed, so as 90 to bring the blade into contact with the stones.

A small grooved wheel 25 is mounted on the hub of the driving-wheel to enable the machine to be driven by a motor, if desired. 95

The driving-wheel being turned to the right, the stones will be rotated in the direction indicated by the arrows, so that the action upon the blade is upward away from the edge, enabling the razor to be honed as desired by applying sufficient downward pressure to the blade to hold it in contact with the stones. Oil, soapy water, or other suitable lubricant may be placed upon the stones during the operation of honing.

Instead of using the belt 16 and the grooved wheels 8 and 9 the shafts carrying the cylindrical stones may be driven by a train of gearing without departing from the spirit of my invention.

Having thus fully set forth my invention, what I claim as new, and desire to secure by Letters Patent, is—

1. In a razor-honing machine, the combination of the cylindrical stones, rotatively mounted and held yieldingly in peripheral contact, a supporting-plate for the razor-blade to direct the blade between said stones, and springs for supporting said plate to allow of a vertical movement thereof.
2. In a razor-honing machine, the combination of the shafts, the cylindrical stones thereon, springs connecting the ends of said shafts, a driving-wheel, pulleys upon said shafts adapted to carry a belt from the driving-wheel, an idle wheel engaging said belt, and means for directing the blade to the

grinding-stones and permitting of a vertical reciprocation thereof.

3. In a razor-honing machine, the combination of the cylindrical, rotative stones, means for mounting said stones to allow of a lateral adjustment thereof, means for supporting a razor movably in place over said stones to permit of a vertically-reciprocatory movement thereof when grinding, and means for driving the stones to rotate them in unison in opposite directions.

In testimony whereof I sign this specification in the presence of two witnesses.

CHARLES F. BOLDT.
